(57) **CLAIM**

The ornamental design for a tablet holder, as shown and described.

DESCRIPTION

FIG. 1 is a perspective view of a stand for a tablet device of the present invention;

FIG. 2 is a front view of FIG. 1 of the present invention;

FIG. 3 is a left side view of FIG. 1 of the present invention; the right side view is a mirror image thereof;

FIG. 4 is a top view of FIG. 1 of the present invention;

FIG. 5 is a rear view of FIG. 1 of the present invention;

FIG. 6 is a bottom view of FIG. 1 of the present invention;

FIG. 7 is a perspective view of a stand for a tablet device of an alternative embodiment of the present invention;

FIG. 8 is a front view of FIG. 7 of the present invention;

FIG. 9 is a left side view of FIG. 7 of the present invention; the right side view is a mirror image thereof;

FIG. 10 is a top view of FIG. 7 of the present invention;

FIG. 11 is a rear view of FIG. 7 of the present invention;

FIG. 12 is a bottom view of FIG. 7 of the present invention;

FIG. 13 is a perspective view of a stand for a tablet device of third alternative embodiment of the present invention;

FIG. 14 is a front view of FIG. 13 of the present invention;

FIG. 15 is a left side view of FIG. 13 of the present invention; the right side view is a mirror image thereof;

FIG. 16 is a top view of FIG. 13 of the present invention;

FIG. 17 is a rear view of FIG. 13 of the present invention; and,

FIG. 18 is a bottom view of FIG. 13 of the present invention. The broken lines shown in the drawings represent portions of the tablet holder and tablet that form no part of the claimed design.

1 Claim, 9 Drawing Sheets
